UNITED STATES PATENT OFFICE.

JOHN W. PAGE, OF CHICAGO, ILLINOIS.

EXCAVATING-SHOVEL.

1,328,013.

Specification of Letters Patent. Patented Jan. 13, 1920.

Application filed March 17, 1919. Serial No. 283,031.

To all whom it may concern:

Be it known that I, JOHN W. PAGE, a citizen of the United States, residing at 1326 Fargo avenue, Chicago, in the county 5 of Cook and State of Illinois, have invented a new and useful Improvement in Excavating-Shovels, of which the following is a specification.

My invention relates to certain new and 10 useful improvements in excavating shovels and is fully described and explained in the specification and shown in the accompanying drawings, in which—

Figure 1 is a side elevation of my improved device, Fig. 2 is a horizontal section on the line 2 of Fig. 1 and Fig. 3 is a vertical section on the line 3 of Fig. 1.

Referring to drawings, 4 is the body of the bucket, such as is well known in the 20 art, and is familiar to excavation engineers under the name of the Page bucket. The bucket is pivotally supported by a bail 5, preferably of chain, which is in turn carried by a hoisting rope 6. 7 is the rear end of 25 the loading line. 8 is the characteristic holding line, forming a part of what is now known as the Page hitch, the same running over a sheave 9 being attached to the front of the bucket. 10 is one of the two continuations of the hauling line, also forming 30 a part of the Page hitch, the two parts running, in accordance with common practice, to opposite edges of the front of the bucket.

Heretofore various expedients have been 35 employed for securing the chains 10 to the bucket, and a great deal of annoyance has been occasioned by wear at the point of attachment. The present invention illustrates a device which I have found affords 40 a very simple and desirable means of attachment, and one which not only very largely decreases wear, and makes replacement very much easier, but has other incidental results which will hereinafter appear.

45 11 is a plate of metal, doubled upon itself to embrace the vertical side wall of the bucket at the front edge, so as to leave a vertical opening. The front doubled or curved edge of this member 11 is provided 50 with two or more horizontal slots. In small buckets only two slots need be used, but in larger ones, such as are here illustrated, it is desirable to use three and sometimes even more such slots to secure adjustment. At 55 the rear end of the chain 10 is a clevis 13, each of whose ends is provided with an eye

14 adapted to enter one of the slots 12. 15 is a vertical pin, which is set inside the curve of the member 11, passes through the eyes of the clevis and is held in place by a cross-bolt 16.

By this construction a very firm and substantial attachment is secured for the chain 10. Owing to the long bearing of the pin 15 in the curve of the plate 11, there is substantially no wear of the plate 11, but the wear falls on the eyes of the clevis and the pin 15. Either or both of these parts can be replaced in a minute or two, practically without tools. The clevis can be adjusted 60 vertically to modify the digging effect if desired.

Aside from the obvious advantages arising from the simplicity and durability of the attaching device, the cost of the bucket 75 proper is considerably reduced by this mechanism. It is well known that the digging characteristics of a Page bucket are determined very largely by the distance forward and above the line of the cutting edge, at 80 which the point of attachment of the hitch is located. In the present device the clevis, of course, while capable of swinging on a vertical pivot in a horizontal plane, cannot swing in a vertical plane, and therefore in 85 determining the digging efficiency we do not consider the point at which the clevis is attached to the bucket, but on the contrary, the point at which the chain 10 engages the clevis. In other words, from the standpoint 90 of digging efficiency, the clevis, might just as well be a rigid part of the bucket. The same efficiency is therefore produced as would be the case if the bucket were made several inches longer, and in point of fact, with the 95 use of the present device, the buckets are actually made several inches shorter on the sides than heretofore, the forwardly extending clevis causing the digging to be done with equal efficiency.

I realize that considerable variation is possible in the details of the construction herein shown, and I do not intend to limit myself thereto, except as pointed out in the following claims, in which it is my intention 105 to claim all the novelty inherent in the device as broadly as is permitted by the state of the art.

What I claim as new and desire to secure by Letters Patent, is—

1. An excavating shovel, having side walls, a plate re-curved upon itself to form

a vertical loop shaped opening and embracing the forward edge of a side wall and attached thereto, a vertical pin in the loop and a clevis pivoted upon the pin and 5 adapted to receive a hauling line.

2. An excavating shovel, having vertical side walls, plates re-curved upon themselves to form vertical loops and embracing the side walls at their forward edges and eyed 10 clevises entering slots in the bent portions of said plates and pins passed through the eyes of the clevises to afford therefor vertical pivots, the clevises being adapted to receive a hauling line.

15 3. An excavating shovel, having vertical side walls, plates re-curved upon themselves to form loops which embrace the side wall and having slots in their bent portions, clevises provided with eyes adapted to enter 20 the slots and to be adjustable in different pairs of slots, pins adapted to lie in the loops of the plates and engage the eyes of the clevises to afford therefor vertical pivots, the clevises being adapted to be engaged by 25 a hauling line.

4. In combination, an excavating shovel having vertical side walls and hauling lines running to the side walls and clevises at the ends of the hauling lines, of means of 30 connection between the clevises and the side walls including removable and replaceable pins having elongated vertical bearings upon the side walls whereby the wear between the pins and the permanent portions of the 35 bucket is reduced to a minimum.

5. In combination, an excavating shovel having vertical side walls and clevises by which the bucket may be dragged for digging and means of connection between the clevises and the side walls including a pin 40 engaging eyes of the clevises and engaging an elongated vertical bearing on the side walls.

6. In combination, an excavating shovel having vertical side walls and having its 45 cutting edge cut back of the forward edges of the side walls, and hauling means secured to the bucket by forwardly extending attaching members pivoted to the bucket side walls upon vertical pivots, whereby the attaching 50 means are rigid with the bucket in a vertical plane.

7. In combination, an excavating shovel having vertical side walls and the cutting edge cut back of the forward edges of the 55 side wall, plates bent back upon themselves to form loops at their forward edges and embracing and secured to the forward edges of the side walls and provided with slots in their bent portions, clevises having horizontal eyes entering the slots and pins lying in the loops of the plates and engaging the eyes of the clevises whereby the clevises are rigid with the bucket in a vertical plane and having the effect, in determining the digging 60 angle of forward extensions of the side walls.

In testimony whereof I have hereunto set my hand and seal this 14th day of March, 1919.

JOHN W. PAGE. [L.S.]
